UNITED STATES PATENT OFFICE.

DOWNES ELLAND NORTON, OF LONDON, ENGLAND.

TOBACCO-PIPE FILLER AND POUCH FOR USE THEREWITH.

1,104,068.

Specification of Letters Patent.

Patented July 21, 1914.

Application filed April 14, 1911. Serial No. 621,077.

To all whom it may concern:
Be it known that I, DOWNES ELLAND NORTON, a subject of the King of Great Britain and Ireland, residing at Laurel Dene, 5 Hampton Hill, London, S. W., England, gentleman, have invented certain new and useful Improvements in and Relating to Tobacco-Pipe Fillers and Pouches for Use Therewith, of which the following is a 10 specification.

This invention relates to tobacco pipe fillers and pouches for use therewith, and has for its object to provide simple means for effectively filling a pipe without the necessity of the use of tobacco made up into cartridges.

According to the invention a pipe filler is provided consisting of a cylindrical member having a cutting edge by which a pipe 20 charge may be cut from a packet or block of tobacco, and a plunger fitting within the cylindrical member by which the charge may be pressed home into the pipe bowl. Means are provided whereby the 25 plunger may be retained in the rearward position or at an intermediate position in the cylindrical member in order to permit a full charge or small charge of tobacco to be cut as may be required, the projecting extremity of the plunger in either of these 30 positions serving as a handle by which the cylindrical member may be operated as a cutter.

According to the invention also a receptacle is provided for tobacco having a suitable aperture into which the pipe filler may be fitted while the receptacle is closed.

The invention is illustrated, by way of example in the accompanying drawings, in 40 which—

Figure 1 is a sectional view of a pipe filler according to the invention, in the open position. Fig. 2 is a sectional view of a modified form of the pipe filler. Fig. 3 is a 45 sectional view of a further modification of the pipe filler in the open position. Fig. 4 is a view corresponding thereto, showing the filler in the collapsed position. Fig. 5 is a front elevation of a pipe filler fitted to 50 a pouch. Fig. 6 is a side view corresponding thereto.

In carrying the invention into effect according to one modification as illustrated

in Fig. 1 the cylindrical member *a* is provided as an open-ended tube, one end of 55 which is provided with a cutting edge *a*¹ by which, upon pressing the said member into a block or packet of tobacco, a pipe charge may be cut. One or more stops may be provided upon the tube adjacent the cutting 60 edge to contact with the edge of the pipe bowl when the charge is being transferred and thus prevent the member *a* from entering the pipe bowl.

A cylindrical plunger *b* of the full length 65 of the cylindrical member and provided with a handle or head *b*¹ at one end is adapted to slide within the cylindrical member for the purpose of ejecting the charge of tobacco therefrom into the pipe bowl, and 70 an outer sleeve member *c* may be fixed to the head *b*¹ and be adapted to slide on the outer surface of the cylindrical member *a*.

A leaf spring or equivalent resilient device 75 may be let into the surface of the plunger so as to contact with the interior of the cylindrical member *a* to prevent the plunger from moving loosely therein.

A longitudinal slot *c* is advantageously provided in the plunger *b* with which may 80 engage a projecting pin or the like *c*¹ mounted upon the cylindrical member *a* so that the movement of the plunger in each direction is limited by the contact of the pin with the respective ends of the slot.

At the end of the longitudinal slot near the cutting edge of the cylindrical member *a* there is provided a short substantially transverse slot *c*², with which upon slight rotation of the plunger, the pin *c*¹ may be engaged and thus retain the plunger in its rearward position while a charge of tobacco is cut, the forward end of the plunger serving to determine the size of the charge.

In the modification illustrated in Fig. 2, 95 in order to provide for cutting charges of several different sizes, the plunger *b* is provided with a spring catch or pin *d*¹ mounted in a slot or recess therein and adapted to engage with one of a series of holes or recesses *d*² formed in the member *a*, the size of charge cut being determined according to which of the holes or recesses *d*² is engaged by the catch or pin *d*¹. Suitable means 100 may be provided to prevent relative rotational movement of the member *a* and plun- 105

ger b , such, for example, as a pin and slot device.

A slightly different construction to those hereinbefore described is shown in Figs. 3 5 and 4. The cylindrical member a is provided relatively short and is engaged with a plunger b and outer sleeve e of corresponding length by means of a pin and slot device as described with reference to Fig. 1 of the 10 drawings. A cylindrical handle portion f is mounted to telescope upon the said sleeve and is retained in its extended position by means of an internally projecting pin f^1 engaging in the transverse portion of the slot 15 in the sleeve e . By such a construction the length of the device may be reduced when not in use as the handle portion may be telescoped upon the plunger sleeve, and the cylindrical member telescoped between the 20 sleeve and the plunger.

The plunger may be provided hollow as a receptacle for matches or other articles and a pin b^1 may be carried in the head b^1 for the purpose of cleaning pipes, which pin, 25 may be received into the plunger.

It will be understood that the connecting pin c^1 may alternatively be carried by the plunger b to engage a slot c formed in the cylindrical member a . If, however, the capacity for cutting charges of different size is 30 of no importance, the pin or slot device may be replaced by a simple spring catch carried by the plunger or outer sleeve adapted to engage the inner extremity of the member a . It may prove advantageous in cases where the plunger or plunger head is provided as a receptacle for matches to form the head end of the plunger and member a of an increased diameter.

40 A suitable pouch for use with the filler is illustrated in Figs. 5 and 6 of the accompanying drawings.

A receptacle or pouch g of indiarubber is provided having at the top or side a circular aperture or ring g^1 which may be fitted around the pipe filler or into which the pipe filler may be introduced. This aperture or ring may be lined with a metallic ring h to which the indiarubber or material 45 of the receptacle or pouch may be secured in any convenient way and the pipe filler may conveniently fit this ring in such manner as to be capable of ready removal. For this purpose the ring may be split or slotted 50 as at h^1 to cause it to contract slightly upon the filler.

The pouch may be provided with an aperture g^2 through which tobacco may be introduced and such aperture may be closed by 60 a flap g^3 secured at each side to the body of the pouch and adapted to be turned back to expose the aperture. The ring h or fitting may alternatively be formed as a lazy-tongs device so that the aperture is capable 65 of being enlarged as may be required for

the introduction of the tobacco into the pouch or receptacle and such a ring may be provided with any convenient means for locking it in its closed position.

What I claim as my invention and desire 70 to secure by Letters Patent is:—

1. A pipe filler, consisting of an open-ended cylinder member of a diameter corresponding to that of the internal bore of a pipe, said cylinder member having a cutting edge at one end adapted to receive and cut a charge of tobacco, a second cylinder member disposed within the first cylinder member and adapted to act as a plunger, and means consisting of a bayonet slot and pin 75 for connecting the said cylinder members together so that pressure may be applied through the second cylinder member for cutting the charge and filling it into the open end of the first cylinder member, said 80 means permitting the disconnection of the respective cylinder members so that the charge of tobacco cut and received into the open end of the first cylinder member may be discharged, by the movement of the second cylinder member, into the bowl of the 85 pipe, substantially as described. 90

2. A pipe filler, consisting of an open-ended cylinder member of a diameter corresponding to that of the internal bore of a 95 pipe, said cylinder member having a cutting edge at one end adapted to receive and cut a charge of tobacco, a second cylinder member disposed within the first cylinder member and adapted to act as a plunger, 100 means consisting of a bayonet slot and pin for connecting the said cylinder members together so that pressure may be applied through the second cylinder member for cutting the charge and filling it into the 105 open end of the first cylinder member, said means permitting the disconnection of the respective cylinder members so that the charge of tobacco cut and received into the open end of the first cylinder member may 110 be discharged, by the movement of the second cylinder member, into the bowl of the pipe, and said means also permitting of cutting and producing charges of various size, substantially as described. 115

3. A pipe filler, consisting of an open-ended cylinder member of a diameter corresponding to that of the internal bore of a pipe, said cylinder member having a cutting edge at one end adapted to receive and cut a charge of tobacco, a second cylinder member disposed within the first cylinder member and adapted to act as a plunger, means consisting of a bayonet slot and pin 120 for connecting the said cylinder members together so that pressure may be applied through the second cylinder member for cutting the charge and filling it into the open end of the first cylinder member, said means permitting the disconnection of the 125 130

respective cylinder members so that the charge of tobacco cut and received into the open end of the first cylinder member may be discharged by the movement of the second cylinder member into the bowl of the pipe, and a receptacle for the tobacco to be cut, substantially as described.

In testimony whereof I have hereunto signed my name to this specification in the presence of two subscribing witnesses.

DOWNES ELLAND NORTON.
